UNITED STATES PATENT OFFICE.

CARLETON ELLIS, OF LARCHMONT, NEW YORK, ASSIGNOR TO ELLIS-FOSTER COMPANY,
A CORPORATION OF NEW JERSEY.

PROCESS OF MAKING SOAP POWDERS.

1,040,530.

Specification of Letters Patent.

Patented Oct. 8, 1912.

No Drawing.

Application filed March 13, 1908. Serial No. 420,765.

To all whom it may concern:

Be it known that I, CARLETON ELLIS, a citizen of the United States, residing at Larchmont, in the county of Westchester 5 and State of New York, have invented certain new and useful Improvements in Processes of Making Soap Powders, of which the following is a specification.

This invention relates to processes of 10 making soap powders or soap material, preferably in a powdered form, and relates particularly to the production of light and fluffy hydrated soap powders having the desirable feature of extreme solubility in 15 water.

The present methods of manufacturing soap and soap powders mostly involve the protracted and costly method of saponifying the grease, or soap stock, with alkaline 20 solutions, salting out the soap, crutching and setting in frames, and subsequently slicing, drying, reducing to a granular condition, redrying and grinding to a powder, or mixing with soda ash, or other detergent 25 or filling material. The manipulation, etc., which these preparations have to undergo makes them relatively dense and insoluble which is disadvantageous since the great 30 advantage to be derived from the use of soap powders over cake soap is the rapidity of their solution in water. The more soluble a soap powder, the more commercially useful it will be found.

My invention involves the manufacture 35 of soap powders and similar soap material without the use of a large quantity of water for the purpose of saponification, and by a method which brings about the direct combination of the soap stock and alkali, so as 40 to form a soap product which is light, fluffy and porous and of extreme solubility.

There have been proposed a number of 45 so-called quick processes, which are mostly inoperative, or produce unsatisfactory products, through inability to properly combine the materials under suitable conditions of 50 operation to produce a soluble efficient detergent. I have found that fatty acids produced in the autoclave hydrolysis of greases 55 are particularly susceptible to combination with alkalis under certain conditions, as will be hereinafter described. I have found, however, that the mixed fatty acids, such as are ordinarily produced from the autoclave saponification of common fats, do not

yield ordinarily a product as satisfactory as does the oleic acid which these fatty acids contain. I prefer, therefore, to press out from this so called "still stock", the red oil, or oleic acid, and use this liquid oil, or 60 fat acid material, for treatment in accordance with my process. I have found that the product from red oil has greater detergent property than soaps made from the mixed acids, or from the individual acids, 65 stearic or palmitic acids. The red oil soap products have the additional advantage of not gelatinizing to the same extent when hot solutions of such soaps are cooled. It is probable also that the oleic mixtures made by 70 my process are less hydrolyzed in solution, so that their causticity is not as pronounced as ordinary soap compositions. My process involves the treatment of such soap stock, preferably red oil, as stated, with an excess 75 of soda ash and with water in such relative proportions that a dry product quickly results from the mixture and in such a manner that the spontaneous heat of reaction between the red oil and the soda ash, as well 80 as the heat of the solution, or hydration, of the soda ash, brings about the complete or substantially complete saponification of the soap stock. This permits of the manufacture of the product without the use of steam 85 or steam jacketed kettles or heating apparatus, so that the operation may be conducted, so to speak, in the cold, although the spontaneous rise in temperature, due to 90 the reaction, causes the mass to attain a temperature of 125 to 135 F., more or less, according to the conditions of operation. This spontaneous heating, which eliminates the necessity of steam jacketed kettles, or 95 the blowing in of steam into the mixture, greatly simplifies the process of manufacturing, reduces the cost of machinery, materially shortens the time of manufacture 100 and furnishes a product which has certain novel qualities, as will be hereinafter described.

By mixing red oil with anhydrous sodium carbonate or soda ash, and subsequently adding a limited quantity of water, a plastic mass results. The water and oil incorporate together because of the emulsifying power of the alkali and of the soap which forms. The oil and the water coöperate together 105 to form the fluid component of the magma. The dry soda carbonate in taking up this 110

water as it soon does, evolves considerable heat and in turn the oleic acid in reacting upon the sodium carbonate evolves still further heat, so that the mass becomes 5 spontaneously heated, thereby accelerating the internal reactions. One of these reactions is of course the liberation of carbon dioxid from the carbonate in saponifying the oleic acid. And this gas generating 10 interiorly of the mass puffs it up into a more or less vesicular body. After completion of the reaction, if the proper amount of water has been employed, and after the mass is cooled down to ordinary temperature, it 15 forms a light, fluffy and readily disintegrating body of dry soap. This mass is readily reduced to a fine powder, and the particles of the powder are also fluffy, since they result from breaking down the vesicular mass 20 and are naturally in large part curvilinear. Particles such as these float in water and do not form the hard compact dough which is formed under similar circumstances by a soap powder consisting of dense, hard particles. 25

An illustrative formula setting forth my at present regarded preferred embodiment, is made by mixing together in a suitable mixing device, such as a tub, or kettle with 30 revolving stirrers, a charge consisting of 20 lbs. of red oil, 50 lbs. of soda ash and 15 quarts of water, or about a third of the amount of water necessary to completely hydrate the soda ash. The amount of soda 35 ash is considerably larger than that equivalent to the red oil. The red oil is preferably run into the mixer first, this is immediately followed by the soda ash and then the water is quickly added. The mixture forms a 40 pasty mass, the temperature of which spontaneously rises to about 130 F. and this paste is run from the mixer on to a cooling floor, where it is allowed to remain undisturbed and where it quickly cools and hardens. During the cooling operation, a peculiar 45 phenomenon evinces itself. The mass undergoes a sort of disintegration whereby it becomes extremely friable and spongy, being intimately vesiculated by the evolved 50 carbon dioxid, and swells in volume. The phenomenon is optically somewhat like that of the slaking of lime, except that in the case of the soap mixture described, the expansion in volume is not nearly as great as 55 that which occurs in the slaking of lime. The expansion which does occur, however, is sufficient to break up the hard lumps and particles into fine soft powdery material, which can be reduced to the size of the 60 grains of ordinary soap powder by merely rubbing between the hands. Hence a very simple grinding machine may be used for reducing it to a powdered form, giving soap grains each of which is intimately porous 65 or vesiculated. This expansive disintegra-

tion or self-pulverization, while not changing the product chemically, constitutes an improvement in the art of soap manufacture, in that the grinding machinery may be of extremely simple construction, so that 70 the combined system of saponifying by the quick process above described, and grinding the spontaneously comminuted or disintegrated product, reduces the time of manufacture and cost of machinery, also the labor 75 involved, to a minimum; which is a very important consideration in view of the great competition prevailing at the present time in the manufacture of such preparations.

I may, of course, use various other soap 80 stocks with the red oil, or with the other fatty acids mentioned above, and for a cheap preparation may add a considerable proportion of rosin. I have, for instance, made up numerous compositions consisting of red 85 oil and rosin, or still stock and rosin, in varying proportions. One formula which I find fairly satisfactory for a cheap article, consists of 1 lb. each of red oil and rosin, 5 lbs. of soda and 3 pints of water. The 90 rosin should be melted with the red oil before the addition with the soda ash and water.

Various abrasive materials may be added, if desired, such as tripoli, ground pumice 95 stone, silex, or rotten stone, and the like. The usual detergent materials such as borax, and the like, or fillers such as sodium sulfate, talc, etc., may also be introduced.

For certain purposes, where a very caustic 103 product is desired, I make use of caustic soda or caustic potash in small amount in connection with the described substances. Such a mixture may be made by mixing 2 lbs. or so, of red oil, $4\frac{1}{2}$ lbs. of soda ash and 105 $\frac{1}{2}$ lb. of caustic soda, to which is added about 3 pints of water. Under certain circumstances, I find it possible to add the water through the agency of washing soda. Crystallized sodium carbonate contains some 110 60% of water, and by grinding the crystals, or crushing them and mixing with the soda ash and red oil, the water may be added in that form, and I find under certain circumstances that this is a useful method of procedure, but it affords the disadvantage of 115 making a rather denser product, which does not heat spontaneously to the same temperature, and which often times requires artificial heat to bring about the desired action. The denser product which is produced by this method does not yield as soluble a soap as the products above mentioned. It is better to add the quantity of water necessary directly in lieu of using 120 crystallized sodium carbonate to furnish it. I have, however, observed that when caustic soda is introduced into the soap powder for the purpose of making a caustic preparation for certain purposes, that if the proc- 125 130

ess is conducted by the direct addition of water, that the resulting soap powder is disposed to exhibit slight hydroscopic properties which often times are undesirable. 5 If, however, it is made through the addition of washing soda to supply water for the reaction, the product is of a satisfactory character, and may be preserved for a long period of time without becoming damp or lumpy. Crystallized carbonate of soda may 10 be therefore used to some extent in connection with mixtures containing caustic soda.

Suitable formulæ illustrative of these methods of operation comprises, for a non-caustic preparation, 2 lbs. of red oil, 4 lbs. 15 of soda ash and 4 lbs. of carbonate of soda crystals. The caustic preparation may be made by mixing 1 lb. of mixed fatty acids or still stock, 1 lb. of red oil, 4 lbs of soda ash, 1 lb. of caustic soda and 3 lbs. of carbonate of soda crystals. Gentle heating often facilitates the reaction and tends to 20 make a more uniform product where the water is supplied through the agency of the crystallized carbonate of soda. While it 25 is desirable in this case to crush the crystallized soda so as to pass, say a 20 mesh sieve, I have also operated with a much coarser material, and even with the large crystals 30 themselves.

For textile work it is sometimes desirable to have a considerable proportion of potash present in the soap powder, and a suitable composition containing potash is made by 35 treating in a similar manner 25 parts of potash, 25 parts of soda ash, 20 parts of red oil and 10 parts of still stock to which are added some 10 or 15 parts of water.

Various perfuming agents may be used in 40 these mixtures, such, for instance, as small percentages of safrol, oil of mirbane, oil of lemon grass, and the like.

The soap composition made with washing soda crystals is better adapted for compression or formation into cakes or chip soap 45 than is that made by the employment of soda ash and water. I find it possible to make solid cakes of attractive appearance containing considerably more saponified 50 matter than is desirable in the use of soap powders. I also find it possible to incorporate abrasive, or filling material or detergent material, as well as hydro-carbon bodies, such as naphtha or kerosene. It is 55 also possible to add carbolic acid, pine tar, and the like, or carbonate or sulfate of ammonia, to get a soap having special detergent properties.

Instead of using water alone in making 60 soap products above mentioned, I may, of course, use solutions such, for instance, as a solution of silicate of soda. For making soap powder, the process should, however, be preferably conducted along the lines set 65 forth above, that is to say, a predominating

amount of soda ash should be mixed with a lesser amount of free fatty acid, preferably red oil, and preferably with water in an amount intermediate the quantity of soap stock and the quantity of soda ash employed, 70 whereby reaction rapidly occurs and a pasty material is produced having by virtue of the spontaneous heating occurring from the soap making process and the heat developed by the hydration of the soda ash, 75 its soap stock completely saponified furnishing a product which on cooling, expansively comminutes or disintegrates to form pulverulent, or partially pulverized, saponaceous material capable of being rapidly 80 and efficiently ground or sifted to the degree of fineness required in commercial soap powders.

While the specific method of mixing as above set forth is to be recommended the 85 procedure may be varied through the addition of the ingredients in different ways or sequence. Hot water may be used if desired and the addition of the water may be made gradual. It should be observed that 90 the amount of water used is insufficient to dissolve the alkali employed; whereby hydrated or partially hydrated carbonated alkali results. The partially hydrated carbonated alkali also may be obtained by 95 mixing a nearly anhydrous alkali such as soda ash with a hydrated alkali such as washing soda, with the disadvantage however that with the latter mixture less spontaneous heating occurs.

Having described my invention, to the details of which I, of course, do not wish to be limited, what I claim is:—

1. The process of making a soap product which comprises mingling a free fatty acid with dry soda ash and water in amount sufficient to institute a reaction while insufficient for the solution of said soda ash, said mingling being done at ordinary temperatures, allowing the mixture to heat spontaneously until a self-disintegrating product is obtained and to cool undisturbed, and comminuting the product.

2. The process of making a soap product which comprises mingling about 2 parts of red oil, about 5 parts of dry soda ash and about 3 parts of water, said mingling being done at ordinary temperatures, allowing the mixture to heat spontaneously until a self-disintegrating product is obtained and to cool undisturbed, and comminuting the product.

3. The process of making a soap product which comprises mingling a free fatty acid with an alkaline composition capable of developing heat on hydration, mixing with water in amount sufficient to develop such heat while insufficient to dissolve such alkaline composition, said mixing being done at ordinary temperatures, and allowing the

mixture to heat spontaneously until a self-disintegrating product is obtained and to cool undisturbed.

4. The process of making a soap product
5 which comprises mixing a fatty acid with a
dry carbonate of soda, and thereafter ad-
mixing water in amount insufficient to dis-
solve such carbonate, allowing the mixture
to heat spontaneously until a self-disinte-
grating product is obtained and allowing
10 the mixture to cool undisturbed, said admix-
ture being performed at ordinary tempera-
tures.

5. The process of making a soap product
15 which comprises admixing red oil with a

dry carbonate of soda, thereafter adding
water in amount insufficient to dissolve such
carbonate, allowing the mixture to heat
spontaneously until a self-disintegrating
product is obtained and allowing the mix-
ture to cool undisturbed, said addition and
admixture being performed at ordinary
temperatures. 20

In testimony whereof I have affixed my
signature in presence of two witnesses.

CARLETON ELLIS.
